Farnsworth Television and Radio Corporation,
a corporation of Delaware

Application January 10, 1944, Serial No. 517,675

8 Claims. (Cl. 178—7.2)

This invention relates to television systems and particularly to the generation of television signals.

In the operation of television systems it is necessary to impress signals upon the reproducing device containing all of the information necessary to reconstitute the picture substantially in its original form. One item of information comprises the light and shade variations existing between the elemental areas of the television subject. Of substantially equal importance is information regarding the average subject illumination or mean picture brightness. The former ordinarily is represented by a voltage fluctuating relatively rapidly from one value to another. This is the so-called A. C. component of the video signal. The latter ordinarily is represented by a voltage varying relatively slowly from one value to another. This is known as the D. C. component of the video signal. The combination of two components is a fluctuating voltage which, at any instant, is related in value to some fixed reference voltage in correspondence with the absolute brightness of the elemental picture area being scanned.

It is well known in the art that, where a conventionally operated iconoscope is used as an image analyzing device in a television signal generator, it is possible to obtain from the output circuit of the iconoscope only the so-called A. C. component of the video signal. The reason for this is that the iconoscope is essentially an alternating current device. As such, there is available only one reference voltage and that is the average value of the relatively rapidly fluctuating voltage representing light and shade values of the subject. Since these voltage fluctuations do not occur according to any fixed periodicity, the average thereof rarely is symmetrically disposed with respect to the maximum and minimum peaks of the fluctuating voltage. Instead, it is displaced from such a position of symmetry in the direction of the predominant fluctuating voltage value. The result is that, with respect to the average value of the fluctuating voltage, the value of the voltage representing an elemental picture area of given illumination varies in accordance with the mean picture brightness. Thus, the requirement that the fluctuating voltage bear a relationship to a fixed reference voltage in correspondence with the absolute brightness of the elemental picture area is not met. Consequently, a signal voltage of this character is unsuitable for use to reproduce accurately a television subject. It, therefore, has been nec-

essary in prior uses of image analyzing tubes of the iconoscope type to employ auxiliary apparatus to provide a voltage representative of the mean picture brightness to which may be referred the values of the fluctuating voltage obtained from a tube of this character in order to produce a video signal suitable to reproduce satisfactorily the television subject.

It is an object of the present invention, therefore, to provide a television signal generator employing an image analyzing tube such as one of the iconoscope type whereby the signal derived from the tube contains both the video information and the average illumination information.

Another object of the invention is to provide a novel method of generating a television signal whereby to derive a television signal comprising both video and average illumination information from an image analyzing tube of the iconoscope type.

In accordance with the instant invention there is provided an image analyzing tube such as a conventional iconoscope having a mosaic and means for producing an electron beam by means of which to scan the mosaic which is anodically related to the beam producing means. The intensity of the scanning beam is modulated at a carrier frequency during trace intervals. As a consequence there is derived from the output circuit of the iconoscope carrier frequency energy which is modulated in amplitude in accordance with the light and shade values of elemental areas of a television subject. The carrier frequency energy also includes the so-called D. C. component which is the information regarding the average intensity of the subject illumination.

The derived carrier frequency energy is modulated only to a relatively small percentage. Accordingly, a multistage video amplifier is provided to amplify the derived carrier frequency energy sufficiently to produce a peak-to-peak voltage of the modulated portion of sufficient magnitude to render it useful for transmission purposes. In one of the higher video amplifier stages the amplified carrier frequency energy is subjected to a limiting or clipping action whereby to eliminate the unmodulated portion of the energy leaving only the modulated portion for subsequent impression upon the transmitting apparatus.

During retrace intervals of the scanning beam the carrier frequency intensity modulation thereof is interrupted by means controlled by a timing device, thereby reducing the output voltage of the tube substantially to zero. In order not

to produce a discontinuity in the carrier wave radiated from the transmitter, energy having an amplitude independent of video modulation is supplied during retrace intervals under the control of the timing device. The amplitude of this energy is suitable to superimpose thereon a carrier modulation representative of a desired synchronizing signal. Thus, there is developed a composite television signal comprising video, average illumination and synchronizing information components.

For a better understanding of the invention, together with other and further objects thereof, reference is had to the following description, taken in connection with the accompanying drawings, and its scope will be pointed out in the appended claims.

In the accompanying drawings:

Fig. 1 is a schematic circuit diagram, partly diagrammatic, illustrating a preferred embodiment of the invention; and,

Figs. 2 to 7 inclusive are graphical representations illustrating the operating characteristics of apparatus embodying the invention in comparison with conventionally operated apparatus.

Referring now particularly to Fig. 1, there are shown those components of a television transmitting apparatus necessary for a complete understanding of the invention. The image analyzing tube 1 may be a conventional iconoscope having a mosaic 2 and associated metallic signal plate 3. The iconoscope also is provided with the usual collector anode 4 in the form of a wall coating on the interior of the tube envelope which extends down into the neck of the tube. The electron beam for scanning the mosaic is developed and controlled by electron gun apparatus located in the neck of the tube. This apparatus comprises an electron emitting cathode 5, an intensity control electrode 6, a focusing electrode 7 and a second anode 8. The scanning apparatus for deflecting the beam over the mosaic may be conventional and has not been shown for the reason that it forms no part of the present invention and is considered unnecessary to an understanding thereof.

The light which is reflected from a television subject 9 is focused onto the mosaic 2 by means of a suitable optical system diagrammatically represented herein by the lens 11.

The output circuit electrodes of the iconoscope, comprising the signal plate 3 and the collector anode 4, are connected respectively to the terminals of a tuned circuit 12. The tuned circuit includes an inductor 13 connected in parallel with the interelectrode capacitance between the signal plate and the collector anode which is represented by the condenser 14. This circuit is tuned sharply for resonance at a predetermined carrier frequency.

The signal developed in the tuned circuit 12 is impressed upon a utilization circuit including a multistage video amplifier. In the present embodiment of the invention this amplifier comprises 5 stages, each of which includes a multi-electrode vacuum tube. The tubes for the successive stages of the video amplifier are 15, 16, 17, 18 and 19, respectively, and may be of the 6AK5 type or its equivalent. Associated with the output circuits of each of the amplifier tubes 15 to 17 inclusive are tuned circuits 21, 22 and 23, respectively. The circuit 21 comprises the parallel connection of an inductor 24 and the interelectrode capacitance between the anode and the screen grid 25 of the tube 15 and represented by

the condenser 26. The circuit 22 comprises the parallel connection of an inductor 27 and the interelectrode capacitance between the anode and screen grid 28 of the tube 16 and represented by the condenser 29. Similarly, the tuned circuit 23 comprises the parallel connection of an inductor 31 and the interelectrode capacitance between the anode and screen grid 32 of the tube 17 and represented by the condenser 33.

10 The circuits 21 and 23 are tuned sharply for resonance at a frequency which is a predetermined amount higher than the carrier frequency. The circuit 22, on the other hand, is sharply tuned for resonance similarly to the circuit 12 at the carrier frequency. The purpose of this arrangement will be made clear in a following portion of the specification describing the operation of the system.

In the cases of the tubes 15, 16, 17, 18 and 19 the respective suppressor grids 34, 35, 36, 37 and 38 are connected directly to their associated cathodes. The terminals of the tuned circuit 12 are connected respectively to the control grid 39 and the grounded cathode of the first stage amplifier tube 15 in series with a suitable source of unidirectional biasing energy such as the battery 40. One terminal of the tuned circuit 21 and the screen grid 25 of the tube 15 are connected to the positive terminal of a source of unidirectional energy such as a battery 41 of which the negative terminal is connected to ground. By means of this connection space current and screen grid potential are supplied to the first stage amplifier tube 15. The other terminal of the tuned circuit 30 21 is coupled by means of a condenser 42 to the control grid 43 of the second stage tube 16. A leak circuit for the condenser and a suitable biasing circuit for the control grid of the tube 16 comprises the connection of a resistor 44 from the control grid through a source of unidirectional biasing energy such as the battery 45 to ground.

Similarly, one terminal of the tuned circuit 22 and the screen grid 28 of the tube 16 are connected to the positive terminal of the battery 41 in order to provide space current and screen grid potential for the tube 16. The other terminal of the tuned circuit 22 is coupled by means of a condenser 46 to the control grid 47 of the third stage amplifier tube 17. The leak and biasing circuit for this tube comprises the series connection of a resistor 48 and a source of unidirectional biasing energy such as the battery 49 connected between the control grid 47 of the tube 17 and ground.

55 In like manner one terminal of the tuned circuit 23 and the screen grid of the tube 17 are connected to the positive terminal of the battery 41 to provide space current and screen grid potential for the third stage amplifier tube 17. The other terminal of the tuned circuit 23 is coupled by means of a condenser 51 to the control grid 52 of the fourth stage amplifier tube 18. A grid leak and biasing circuit for this tube is provided by the series arrangement of a resistor 53 and a source of unidirectional biasing energy such as the battery 54 connected between the control grid of the tube 18 and ground. In the case of this amplifier stage the potential of the battery 54 is chosen so as to bias the input circuit of the tube 70 sufficiently negative to effect the operation thereof as a class C amplifier. The purpose of this arrangement will be made clear in a following portion of the specification in which the operation of the system is described.

The screen grid 55 of the fourth stage ampli-

filter tube 18 is connected to the positive terminal of the battery 41 to provide a suitable potential to this electrode. The anode of this tube is connected through an inductor 56 to the positive terminal of the battery 41. Another inductor 57 is cooperatively arranged with respect to the inductor 56 to receive energy therefrom. The terminals of the inductor 57 are connected to the terminals of a voltage developing resistor 58. The inductors 56 and 57 are mutually arranged in a manner to form a bandpass coupling circuit. One limiting frequency of the band is substantially equal to the frequency to which the circuits 21 and 23 are tuned and the other limiting frequency is substantially equal to the frequency to which the circuits 12 and 22 are tuned.

One terminal of the resistor 58 is connected to the control grid 59 of the fifth stage amplifier tube 19. The other terminal of the resistor is connected through a source of unidirectional biasing energy such as the battery 61 to ground. This battery is shunted by a by-pass condenser 62 for the purpose of providing an alternating current circuit to ground for the input circuit resistor 58. The screen grid 63 of the tube 19 is connected to the positive terminal of the battery 41 to provide a suitable operating potential for this electrode. The anode of this tube is connected through an output circuit inductor 64 to the positive terminal of the battery 41. The tube 19 may be of the same type as the tubes 15 to 18, inclusive, if desired, and may be connected as described, whereby the suppressor grid thereof is not utilized.

There is inductively coupled to the output inductor 64, another inductor 65 which may be connected to additional amplifying apparatus if desired, or as shown, directly to a transmitter 66 whereby the modulated carrier wave energy may be converted into a form suitable to be transmitted from a radiator 67.

The transmitter system also includes a source of carrier wave energy such as a local radio frequency oscillator 68. The frequency of this oscillator may be selected for any desired relationship to the radiated carrier wave. For convenience in the present instance it is less than the radiated wave. However, in the following portions of the specification and in the claims the expression "carrier frequency wave" is used to denote any desired frequency such as a sub-carrier or intermediate frequency or even the radiated frequency. This oscillator is connected to two separate circuits, one of which includes a carrier wave amplifier 69. The output terminals of this amplifier are connected to an inductor 70 with which there is cooperatively arranged for the inductive transfer of energy an inductor 71. One terminal of this latter inductor is connected to the intensity control electrode 6 of the electron gun. The other terminal of the inductor 71 is connected through a current limiting resistor 72 to the adjustable slider contact 73 of a potentiometer 74. The resistor 72 and the potentiometer 73 are shunted by a by-pass condenser 75.

The potentiometer 74 is connected in series with resistors 76 and 77, another potentiometer 78 and a source of unidirectional energy such as the battery 79. The positive terminal of this battery is connected to ground and the negative terminal to one terminal of the potentiometer 74. The adjustable sliding contact 80 of the potentiometer 78 is connected to the focusing anode 7 of the electron gun.

The second circuit to which the radio frequency

oscillator 68 is connected also includes a carrier wave amplifier 81 the output terminals of which are connected to an inductor 82. This inductor is cooperatively arranged with respect to the inductor 57 for the transfer of carrier wave energy to the input circuit of the tube 19.

The carrier wave amplifiers 69 and 81 are controlled by signals derived from a blanking and synchronizing signal source 83. This signal source is connected to the biasing circuits of the amplifiers 69 and 81 in a manner to render these amplifiers operative alternately for a purpose to be described in a following portion of the specification relating to the operation of the system.

Referring now to the operation of the described apparatus, assume that the various electrodes of the electron gun housed in the neck of the iconoscope 1 are provided with appropriate potentials. The sliding contact 80 is adjusted to a point on the potentiometer 78 to impress a suitable potential upon the focusing anode 7 to effect the desired focusing of the electron beam. Also, the sliding contact 73 is adjusted to a point on the potentiometer 74 such that the magnitude of the biasing potential impressed upon the intensity control electrode 6 is suitable to completely interrupt the flow of electrons past the electrode in the absence of the development of carrier wave energy in the inductor 71. The switching arrangement provided for the carrier wave amplifiers 69 and 81 is of such a character that the amplifier 69 is conditioned for operation and the amplifier 81 is inoperatively conditioned during trace intervals of the electron beam over the iconoscope mosaic 2. During retrace intervals the carrier wave amplifier 81 is operatively conditioned and the carrier wave amplifier 69 is inoperatively conditioned. This amplifier switching is under the control of the synchronizing signal source 83.

During trace intervals in the scanning operation the electron beam is modulated in intensity at the frequency of the carrier wave source which may be of the order of 20 megacycles. Consequently, as the beam is bombarding each elemental area of the mosaic 2 it will be modulated in intensity through a number of cycles of the carrier wave. The signal voltage which is developed between the signal plate 3 and the collector anode 4 then is a carrier wave at the frequency of the radio frequency oscillator 68 which is modulated in amplitude in accordance with the electrical condition obtaining at the successive elemental areas of the scanned mosaic. The depth of modulation of the carrier wave may not exceed a modulation of the order of 10%.

In order to use this type of signal it is necessary to increase the relative magnitudes or ratio of the voltage representing picture black and that representing picture white. For this purpose the relatively low percentage modulated carrier wave is impressed successively upon the plurality of video amplifier stages arranged in cascade. The multistage video amplifier provided herein must be capable of amplifying the modulated carrier wave together with a predetermined number of its side band frequencies produced by the modulated video signal. Accordingly, the amplifier is designed to function effectively to amplify a predetermined band of frequencies, including the carrier wave and the desired number of side band frequencies.

The manner in which this is accomplished is by means of the tuned circuits 12, 21, 22 and 23. Inasmuch as the signal voltage developed at the

output circuit of the iconoscope is relatively weak and generally not much in excess of the level of noise effects, it is desirable to tune the circuit 12 sharply for resonance at the carrier wave frequency. By this means it is possible to develop a video signal of a character which has the greatest possible signal-to-noise ratio. However, the specified tuning of the circuit 12 discriminates greatly not only against the noise effects but also against the side band frequencies produced by the video signal modulation of the carrier wave. In the present instance it is assumed that it is desired to produce a video signal modulated carrier which will include, in addition to the carrier wave frequency, only the upper side band frequencies. To this end the circuit 21 is tuned sharply for resonance at that upper side band frequency which has the greatest deviation from the carrier frequency. This arrangement provides a satisfactory compensation for the attenuation of the upper side band frequencies produced by the tuned circuit 12 and the incidental desirable suppression of the lower side band frequencies. In like manner, the tuning of the circuit 22 to the carrier frequency and the circuit 23 to the upper limiting frequency of the upper side band frequencies serve to provide an amplifier having a band-pass characteristic by means of which the carrier and its upper side band frequencies are amplified.

After successive amplifications of the relatively low percentage modulated carrier wave, the voltage difference of the portion representing picture black and the portion representing picture white is increased sufficiently to be usefully employed. However, the larger proportion of the carrier wave energy is unmodulated and can not be usefully employed. It is this type of signal which is impressed upon the input circuit of the amplifier tube 18. The biasing of the input circuit of this tube is of such a character that the stage operates as a class C amplifier. In other words, it is responsive only to signal voltages exceeding a magnitude determined by the negative biasing voltages impressed upon the grid of the tube. In the present instance this signal voltage magnitude is substantially equal to the smallest value of the modulated portion of the carrier wave. Thus, there appears in the output circuit of the tube 18 an amplified carrier wave which is modulated in amplitude in accordance with the video signal and to a relatively high percentage.

The relatively high percentage modulated carrier wave, together with the desired upper side band frequencies, is coupled by means of the inductors 56 and 57 to the input circuit of the fifth stage amplifier tube 19. By reason of the band pass character of the coupling inductors 56 and 57 the modulated carrier wave and its upper side band frequencies are amplified by the tube 19 and coupled to the transmitter 66 for suitable conversion and subsequent radiation.

During retrace intervals in the scanning operation the synchronizing signal source 83 develops a signal under the control of the usual timing apparatus at a time coinciding with the functioning of the iconoscope deflection system whereby the scanning beam is brought back to the starting point of its scanning cycle. This synchronizing impulse is impressed upon the biasing circuits of the carrier wave amplifiers 69 and 81 in suitable polarity to render the amplifier 69 inoperative and the amplifier 81 operative.

The interruption of the supply of carrier wave energy to the intensity control electrode 6 of the

electron gun permits the bias voltage impressed upon this electrode by the sliding contact 73 of the potentiometer 74 to completely interrupt the beam whereby to prevent it from reaching the mosaic 2. This step is commonly known as "blanking" the image analyzing tube. As a consequence, the signal voltage derived from the output circuit electrodes 3 and 4 of the iconoscope is reduced substantially to zero at which value it is maintained for the duration of each retrace interval.

However, during this time, there are provided facilities for preventing a discontinuity of the carrier wave radiated from the transmitter 66. These facilities, in accordance with the present invention, are controlled by the signals generated by the source 83. It is contemplated to be within the scope of the invention to employ the signals originating at the source 83 to control the injection of carrier wave energy at a predetermined amplitude and at the radiated frequency in any one of a number of ways within the skill of those versed in the art. In the case where the carrier wave energy derived from the output circuit of the iconoscope is at a sub-carrier frequency or an intermediate frequency with respect to the frequency of the radiated carrier wave, the injected energy may be at the radiated frequency or at the subcarrier or intermediate frequency. In accordance with the illustrative embodiment of the invention the injected energy is at the frequency of the local carrier wave source 83.

Accordingly, when the carrier wave amplifier 69 is rendered inoperative the carrier wave amplifier 81 is rendered operative under the control of signals derived from the source 83. In this manner local carrier wave energy is supplied to the inductor 82 from which a suitable portion is induced in the inductor 57. Consequently, there is impressed upon the input circuit of the tube 19 carrier wave energy at a predetermined amplitude. This amplitude conveniently may be made to correspond to that representing picture black. In such a case a synchronizing signal may be developed by suitably modulating the carrier wave energy supplied by the amplifier 81 or in an equivalent manner. For example, in television signalling systems using negative modulation during trace periods, the maximum amplitude of the carrier wave represents picture black and the minimum carrier amplitude represents picture white. In such a case, the synchronizing signals may be produced by increasing the amplitude modulation of the carrier wave to exceed the amplitude representing picture black. However, as far as the present invention is concerned it is immaterial whether positive or negative modulation of the carrier wave is employed or what the amplitude relationship of the synchronizing signals to other portions of the carrier wave are. It is considered to be within the skill of those versed in the art to adjust the circuit components suitably to provide the necessary carrier wave amplitude to the transmitter 66 during retrace intervals of the scanning beam.

At the conclusion of each retrace interval the carrier wave amplifier 81 is rendered inoperative and the carrier wave amplifier 69 is again rendered operative under the control of the synchronizing signal source 83. The described cycle of operation is then repeated for each scanning line.

In order more clearly to emphasize the manner in which apparatus in accordance with the present invention functions to provide the information regarding the average subject illumination

in addition to the information regarding the light and shade values of the subject, reference will be made to Figs. 2 to 7, inclusive.

Referring now particularly to Fig. 2, there is represented a picture area having a relatively high average illumination intensity. This area is divided into two portions for the purpose of illustrating the principles underlying the invention. It is assumed that the left hand half of the rectangular picture area 84 represents a television subject having two light values. This portion comprises alternate vertical areas of which the rectangles 85 represent black picture elements and the areas 86 represent lighter picture elements such as, for example, light gray. The right hand portion 87 of the picture area 84 is assumed to have the same light value as the area 86.

Fig. 3 illustrates a typical signal which is generated by means of a conventionally operated iconoscope in scanning the picture area 84 of Fig. 2 in a line extending from left to right. The maximum positive signal peaks 88 represent the black areas 85 and the negative peaks 89 represent the light gray areas 86 and 87. It is a characteristic of an iconoscope, conventionally operated, to generate this type of signal and since it is of an alternating current character the energy content of a positive polarity is equal to the energy content of a negative polarity for any given time interval, such as the scanning time for one line. Inasmuch as the proportion of the total light gray areas to the total black areas of the picture 84 is the ratio of 3 to 1, the average zero voltage of the generated alternating current signal is disposed relative to the positive and negative voltage peaks in a manner such that the proportion of the positive voltage peaks to the negative voltage peaks also is in the ratio of 3 to 1.

Consider now the case where the average subject illumination is relatively low as compared to that represented by the picture area 84. In Fig. 4 there is illustrated a picture area 91 of the same shape and dimensions as the area 84. In this case the left hand portion is the same as in the area 84, comprising alternate black strips 85 and light gray strips 86. However, the right hand portion 92 of the area 91 is black. It is evident that the average illumination of the picture area 91 is considerably less than that of the picture area 84 of Fig. 2.

The same general type of video signal is generated to represent the left hand portion of the area 91 as that representing the area 84. This condition is represented in Fig. 5 wherein the black strips 85 are represented by positive voltage peaks 88' and the light gray strips 86 are represented by the negative voltage peaks 89'. In this case, however, the proportion of the total light gray areas of the picture 91 to the total black areas thereof is in the ratio of 1 to 3. Consequently, the average zero voltage of the generated alternating current signal representing the picture area 91 is disposed relative to the positive and negative voltage peaks 88' and 89' in a manner such that the proportion of the positive voltage peaks to the negative voltage peaks also is in the ratio of 1 to 3.

It is evident that the signals of Figs. 3 and 5 are not usable without modification for the accurate reproduction of the television subject. The modification required is the incorporation in the signals of the so-called D. C. component. It is well known, of course, that this component may

not be derived from a conventionally operated iconoscope.

Referring now to Figs. 6 and 7 the carrier wave energy derived from the iconoscope operated in accordance with the present invention is represented at 93. Both positive and negative half cycles of the carrier are modulated in amplitude in accordance with the light and shade values of the picture areas 84 and 91, respectively, of Figs. 2 and 4. Consequently, both positive and negative envelopes of the carrier wave correspond respectively to the signal wave forms illustrated in Figs. 3 and 5. Specifically, the black portions 85 and 92 of the picture areas 84 and 91 respectively of Figs. 2 and 4 are represented by the maximum carrier amplitudes 94 and 94' of Figs. 6 and 7. Similarly the light gray portions 86 of Figs. 2 and 4 are represented by the minimum carrier amplitudes 95 and 95' of Figs. 6 and 7.

It is apparent that, by reason of the similar amplitude modulation of both positive and negative half cycles of the carrier wave 93, the alternating current derived from the output electrodes of the iconoscope produces an average zero voltage which is invariably related to the amplitude of the wave irrespective of the average illumination intensity of the television subject. The result is that the instantaneous amplitude of the generated carrier wave always has the same value relative to a fixed reference voltage in correspondence with the absolute brightness of the elemental area being scanned. In this manner the developed voltage may be demodulated, if desired, to recover the modulating component which will contain both the information regarding the light and shade variations of the subject and the information regarding the average subject illumination intensity.

Also, it has been determined in practice that the phenomenon known as shading, when operating an iconoscope in a conventional manner, is substantially entirely eliminated by means of apparatus operating in accordance with the instant invention. Shading is caused by the production of spurious signals incidental to the scanning of the mosaic by the electron beam. Heretofore, in order to minimize the shading effects, it has been common practice to operate an iconoscope with relatively small scanning beam currents. This practice, however, reduces the efficiency of the signal generator. Additionally, it has been necessary to provide facilities for compensating the spurious signal by introducing a similarly shaped signal of opposite polarity to the spurious shading signal.

It has been found that by using the iconoscope as a carrier wave modulator, in accordance with the invention described previously, the spurious shading signals are not present in the signal derived from the output circuit of the iconoscope. For this reason it is possible to increase the efficiency of the iconoscope as a signal generator by employing a scanning beam of materially greater current intensity than heretofore has been possible.

While there has been described what, at present, is considered the preferred embodiment of the invention, it will be obvious to those skilled in the art that various changes and modifications may be made therein without departing from the invention, and therefore, it is aimed in the appended claims to cover all such changes and modifications as fall within the true spirit and scope of the invention.

What is claimed is:

1. In a television signal generator, an image analyzing tube having means for producing a cathode ray and an electrode anodically related thereto, means for deflecting said cathode ray relative to said anodic element, a utilization circuit for said tube coupled to said anodic element, means for modulating the intensity of the cathode ray at a carrier wave frequency, whereby to develop in said utilization circuit, amplitude modulated carrier frequency energy representing video signals, and means for periodically discontinuing the cathode ray modulation and for simultaneously impressing upon said utilization circuit carrier wave energy modulated in amplitude independently of video signals.

2. In a television signal generator, an image analyzing tube having means for producing a cathode ray, a cathode ray intensity control circuit and an output circuit including an electrode anodically related to said ray producing means, means for deflecting said cathode ray relative to said anodic element, a utilization circuit coupled to said output circuit for the development therein of carrier frequency energy suitable for radiation, means for modulating the intensity of the cathode ray at a predetermined alternating current frequency for the development in said utilization circuit of energy at said carrier frequency modulated in amplitude in accordance with video signals, and means for periodically interrupting the modulation of said cathode ray and for simultaneously developing in said utilization circuit carrier wave energy having a predetermined modulation independent of said video signals.

3. In a composite television signal generator, a cathode ray image analyzing tube having a ray intensity control circuit and a signal output circuit, a utilization circuit coupled to said output circuit, a source of radio frequency carrier wave, and means for coupling said carrier wave source alternately to said intensity control circuit and to said utilization circuit.

4. A composite television signal generator comprising, an image analyzing tube having output circuit electrodes, a photo-electric mosaic associated with one of said electrodes and means for producing a concentrated electron beam to scan elemental areas of said mosaic, means for modulating the intensity of said electron beam at a carrier frequency during trace intervals, whereby to develop at said output circuit electrodes carrier frequency energy modulated in amplitude in accordance with video signals and including information regarding the average illumination intensity of a television subject, a utilization circuit coupled to said output circuit electrodes, means for interrupting said electron scanning beam during retrace intervals, and means for simultaneously injecting into said utilization circuit carrier frequency energy modulated in amplitude independently of video signals.

5. A composite television signal generator comprising, an image analyzing tube having output circuit electrodes, a photo-electric mosaic associated with one of said electrodes and means for producing a concentrated electron beam to scan elemental areas of said mosaic, a source of carrier wave, means for coupling said carrier wave source to said image analyzing tube to modulate the intensity of said electron beam during trace intervals at the frequency of said carrier wave, whereby to develop at said output circuit electrodes carrier frequency energy modulated in

amplitude in accordance with video signals and including information regarding the average illumination intensity of a television subject, a video signal amplifier having its input circuit coupled to said output circuit electrodes, a television transmitter coupled to the output circuit of said video signal amplifier, means for coupling said carrier wave source to said video signal amplifier, and means for energizing alternately said two carrier wave coupling means, whereby to interrupt said electron scanning beam during retrace intervals and simultaneously to inject into said video signal amplifier carrier frequency energy modulated in amplitude independently of video signals.

6. A composite television signal generator comprising, an image analyzing tube having output circuit electrodes, a photoelectric mosaic associated with one of said electrodes, and means for producing a concentrated electron beam to scan elemental areas of said mosaic, a source of radio frequency carrier wave, means including a first carrier amplifier for coupling said carrier wave source to said image analyzing tube to modulate the intensity of said electron beam during trace intervals at the frequency of said carrier wave, whereby to develop at said output circuit electrodes carrier frequency energy modulated in amplitude in accordance with video signals and including information regarding the average illumination intensity of a television subject, a video signal amplifier responsive to said modulated carrier frequency energy and having its input circuit coupled to said output circuit electrodes, a television transmitter coupled to the output circuit of said video signal amplifier, means including a second carrier amplifier for coupling said carrier wave source to said video signal amplifier, and timing means for energizing alternately said first and second carrier amplifiers, whereby to interrupt said electron scanning beam during retrace intervals and simultaneously to inject into said video signal amplifier carrier frequency energy modulated to a predetermined amplitude independently of video signals in order to develop at said transmitter a composite television signal including alternate video and synchronizing components.

7. A composite television signal generator comprising, an image analyzing tube having a pair of output circuit electrodes, a photoelectric mosaic associated with one of said electrodes and means for producing a concentrated electron beam to scan elemental areas of said mosaic, a source of radio frequency carrier wave, means including a first carrier amplifier for coupling said carrier wave source to said image analyzing tube to modulate the intensity of said electron beam during trace intervals at the frequency of said carrier wave, whereby to develop at said output circuit electrodes carrier frequency energy modulated in amplitude in accordance with video signals and including information regarding the average illumination intensity of a television subject, a multistage video signal amplifier responsive to said modulated carrier frequency energy and having its input circuit coupled to said output circuit electrodes, a television transmitter coupled to the output circuit of said video signal amplifier, means including a second carrier amplifier for coupling said carrier wave source to one of the latter stages of said video signal amplifier, and means including a source of synchronizing signals for energizing alternately said first and second carrier amplifiers, whereby to interrupt

said electron scanning beam during retrace intervals and simultaneously to inject into said video signal amplifier carrier frequency energy modulated to a predetermined amplitude independently of video signals in order to develop at said transmitter a composite television signal including alternate video and synchronizing components.

8. A composite television signal generator comprising, an image analyzing tube having a pair of output circuit electrodes, a photoelectric mosaic associated with one of said electrodes and means for producing a concentrated electron beam to scan elemental areas of said mosaic, a source of radio frequency carrier wave, means including a first carrier amplifier for coupling said carrier wave source to said image analyzing tube to modulate the intensity of said electron beam during trace intervals at the frequency of said carrier wave, whereby to develop at said output circuit electrodes carrier frequency energy modulated in amplitude in accordance with video signals and including information regarding the average illumination intensity of a television sub-

ject, a multistage video signal amplifier responsive to said modulated carrier frequency energy and having its input circuit coupled to said output circuit electrodes, a television transmitter coupled to the output circuit of said video signal amplifier, one of said video amplifier stages being biased so as to amplify said modulated carrier frequency energy in a manner to increase the modulation percentage thereof, means including a second carrier amplifier for coupling said carrier wave source to one of the latter stages of said video signal amplifier, means including a source of synchronizing signals for energizing alternately said first and second carrier amplifiers, whereby to interrupt said electron scanning beam during retrace intervals and simultaneously to inject carrier frequency energy modulated to a predetermined amplitude independently of video signals into said video signal amplifier in order to develop at said transmitter a composite television signal including alternate video and synchronizing components.
